IGNITION TIMING DEVICE

Clifford Colvin, Detroit, Mich., assignor to
George M. Holley and Earl Holley

Application April 15, 1942, Serial No. 439,065

1 Claim. (Cl. 123—117)

The object of this invention is to vary the ignition advance at wide open throttle without interfering with part throttle ignition advance. The problem is to take care of fuels of varying octane values. If the ignition system as a whole is retarded to eliminate the knock road mileage is lost, because the part throttle spark advance is retarded although the knock occurs chiefly at wide open throttle and at throttle almost wide open, and especially when the throttle is opened quickly, that is, faster than the engine picks up.

The figure shows diagrammatically the essential elements of my invention.

In the drawing, 10 is a bridge supporting the fuel nozzle in the air entrance; 11 is a venturi in which the nozzle discharges; 12 is a throttle located in the mixture outlet 13. A passage 14 communicates with the mixture outlet 13, through a passage 15, the moment the throttle valve 12 is opened a few degrees. The restriction 16 in this passage determines the effect of the suction in the mixture outlet on the ignition advance for road load. A restriction 17 in the passage 14 communicates with the venturi 11 through the opening 18, which is at least equal in area to the opening 17. The restrictions 16 and 17 are so adjusted that when the throttle is partly opened the suction created in the mixture outlet 13 is modified by the lack of suction in the throat of the venturi 11. The resultant of the suction is sufficient to advance the spark sufficiently to give the desired mileage. When the throttle is wide open the suction in the venturi 11 is modified by the lack of suction at the point 15 and again the suction is sufficient to advance the spark the desired amount at wide open throttle.

The suction thus modified is transmitted through the pipe 21 to the chamber 22, one wall of which is formed of a diaphragm 23 connected by a link 24 with an arm 25 of the circuit breaker plate 26. This plate carries the ground contact 30 and the circuit breaker arm 28 which carries the moving contact 29 which is connected through the electric wire 30 with the coil 32, the low tension side of which is connected with the battery 31 and the high tension side is connected to the distributor 33.

It will be noted that when the throttle 12 is closed, the opening 15 is no longer subjected to engine suction so that the engine idles with a retarded spark.

When a low grade fuel is used, a needle valve 19 is opened admitting air from the opening 20 which communicates with the air entrance and so minimizes the effect of the suction in the venturi 11. The effect of opening the needle valve 19 on the part throttle advance is practically nil because the restriction 17 is equal to the restriction 18, so that the reduction in the suction at part throttle is the same as if the needle 19 is closed.

Hence at wide open throttle, the spark advance is not as great as it otherwise would be but the road load spark advance is practically unchanged.

The result is that a low grade fuel can be used without sacrificing very much mileage because tank mileage is determined mostly by part throttle performance, or road load mileage as it is termed. At wide open throttle there will be a loss but high mileage is impossible at wide open throttle.

What I claim is:

In an internal combustion engine a carburetor having an air entrance, a venturi therein, a mixture outlet, a throttle valve therein, an ignition system for said engine including a low tension circuit breaker, a chamber associated therewith having a movable wall, said movable wall being adapted to advance and retard said low tension circuit breaker in response to an increase or a decrease of suction in said chamber, a passage connecting the chamber with the mixture outlet at a point adapted to be subjected to the mixture outlet suction whenever the throttle is moved from its closed position, a restriction in said passage, a second passage connecting the throat of the venturi with the first passage at a point between said restriction and said chamber, a restriction in said second passage, and an adjustable opening admitting the air at substantially atmospheric pressure into said second passage at a point between the restriction therein and the throat of the venturi.

CLIFFORD COLVIN.
